Inventor:
Henry White.

United States Patent Office.

HENRY WHITE, OF CHICAGO, ILLINOIS, ASSIGNOR TO HIMSELF
AND WILLIAM F. WHITEHOUSE, OF SAME PLACE.

Letters Patent No. 90,976, dated June 8, 1869.

VENTILATOR.

The Schedule referred to in these Letters Patent and making part of the same.

To all whom it may concern:

Be it known that I, HENRY WHITE, of the city of Chicago, county of Cook, and State of Illinois, have invented a new and improved Mode of Ventilating Buildings, Vessels, and Compartments Requiring Ventilation; and I do hereby declare that the following is a full and exact description thereof, reference being had to the accompanying drawings, and the letters of reference marked thereon.

The nature of my invention consists in providing an air-chamber, to be located in the building, or any apartment thereof, or in the hold of a vessel, or in any compartment requiring ventilation, at any convenient point, as hereinafter set forth, the air-chamber to be connected with each apartment or compartment to be ventilated by an air-flue or flues, and by an exhaust-flue with a furnace or other heating-apparatus, or with a chimney or conduit for steam, heat, or smoke, or with a flue with coils of steam-pipe therein, by which the air may be heated, rarefied, and exhausted from the air-chamber, and its connection or connections.

To enable others skilled in the art to make and use my invention, I will proceed to describe its construction and mode of operation.

I construct an air-chamber as shown at A, in the accompanying drawings, the size of which would vary according to the number and size of the chambers, apartments, or compartments to be ventilated. In Figure 1 it is shown as sunk beneath the floor of the cellar or basement, and left open for reference. It is a closed chamber; its materials may be wood, metal, brick, or stone; it may be located at any convenient point below where the heat is applied to the exhaust-flue H, but in case it be difficult or inexpedient thus to locate it, it may be placed at any convenient point, provided that the exhaust-flue at some point descends below the level at which heat is applied to operate the exhaust-flue, as shown in Figure 7.

This air-chamber is connected with each room, apartment, or compartment to be ventilated, by one or more air-flues F F, and registers E E, in number and position as may be required, (see Figures 1 and 2,) the air-flues to enter the air-chamber A in or near the bottom.

Then I construct an exhaust-flue, H, from the said air-chamber, in the top or at the side or end of the same, near the top, or as near the top as may be necessary to effect the object desired, viz, the exhaust of the foul air, to the air-chamber B of the furnace D, (see fig. 2,) thence through the air-pipe C to the smoke-flue N, (see Figure 4;) and in order to give force and direction to the current of air, I conduct the smoke-pipe J up the chimney or flue, from seven to ten feet, or so far as may be required to properly utilize the

heat; then, and not till then, the air and smoke commingle, and a draught is given to the fire, and force to the whole current, until its escape into the atmosphere above; or I carry the exhaust-flue H direct to the chimney or other conduit for the escape of heat and smoke, (see Figure 6,) or to a special conduit for that purpose, to or within which heat is applied by steam-coils or otherwise; or, if it be more convenient, instead of extending the smoke-pipe J up the chimney or flue, I carry the exhaust-flue H up the chimney or flue so far as may be necessary to create sufficient draught in the exhaust-flue. (See Figure 9.)

In large buildings or compartments, and where no fires are in constant use, I employ a furnace, D, to produce the heat required, (see fig. 1,) but where opportunity offers, I use the waste heat from steam-boilers, hot-air furnaces, or kitchen-ranges, and stoves, as the case may be, to warm and rarefy the air of the chimney, flue, or conduit, and keep in constant circulation an ascending current of air, and thus exhaust the foul air from the rooms, apartments, or compartments.

The air-pipe C, from the furnace D, (see fig. 4,) must be of sufficient capacity that the atmospheric pressure shall at all times be greater than the force of heat thrown off by the pipe J, that there may be a free circulation.

In case of a single apartment to be ventilated, I deem it sufficient to put a register, E, in the chimney or flue, (see Figure 5,) and create a draught in the chimney or flue above that point by extending the smoke-pipe J up the chimney or flue, or by any of the means above set forth.

I prefer to take the supply of atmospheric or external air from the top of a building by flues and registers in the walls, or by other suitable means, (see Figure 3,) the said flues K and registers I being in number and position as deemed desirable, or from wherever the external air can be obtained to the best advantage for the purposes required or the objects intended.

I do not consider it necessary to this system of ventilation to use the air-flues K (see fig. 3) under all circumstances, as sufficient external air may be received by ordinary means, or from a furnace when in use.

There is no difficulty in drawing cold air down the flues, provided the flues are kept cold.

In case the air that passes through the exhaust-flues is so impure that it would be objectionable that the same should mingle in this condition with the external air, I employ a deodorizer or disinfectant to remove the impurities.

Any deodorizer may be employed, and in any convenient manner may be applied to the foul air. Chloride of lime may be used for this purpose, placed on

one or more wire-gauze trays placed in a small chamber, M, (see Figure 8,) connected with the exhaust-flue H, or in the exhaust-flue H, in such manner that the foul air may pass thoroughly through the same, and the impurities be removed.

The character of the disinfectant or deodorizer, and the manner of its application, would vary in accordance with the circumstances of individual cases, to some extent.

Having thus described my invention,

What I claim as new, and desire to secure by Letters Patent, is—

The combination of the air-chamber A and the exhaust-flue H, and the application thereto of a deodorizer or disinfectant, fig. 8, in manner and form substantially as shown and for the purposes as set forth.

HENRY WHITE.
